UNITED STATES PATENT OFFICE.

GUSTAVE E. VILLARET, OF LEONIA, NEW JERSEY, ASSIGNOR TO GLOBE LIGHTING
FIXTURE MFG. CO., OF BROOKLYN, NEW YORK.

DESIGN FOR A LIGHTING-FIXTURE BRACKET OR ARTICLE OF SIMILAR NATURE.

Application filed April 30, 1927. Serial No. 21,806. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for a Lighting-Fixture Bracket or Article of Similar Nature, of which the following is a specification, reference being had to the accompanying drawing, forming a part thereof.

Figure 1 is an elevational view of a light-

ing fixture bracket showing my new design.

Figure 2 is an edge elevational view of the same.

I claim:

The ornamental design for a lighting fixture bracket or article of similar nature, as shown.

In testimony whereof I affix my signature as shown.

GUSTAVE E. VILLARET.
